Edwin C. Elsner, Pasadena, Calif., assignor to Aeroquip Corporation, Jackson, Mich., a corporation of Michigan

Filed Apr. 11, 1960, Ser. No. 21,540

6 Claims. (Cl. 294—83)

This invention relates to a load-handling device used to suspend a load from a lifting and carrying vehicle, and which may be utilized for automatic release of the load when the weight of the load is released from the device, or, optionally, for manual load release. It is particularly adaptable for use with a crane where manual load release in close proximity of the load would be dangerous, inconvenient or impossible, and also where speed of release is desired. Other uses for the device will be apparent from the detailed description of the device which follows.

It is an object of this invention to provide a device which will securely hold a load in suspension, but will automatically release the load when the load is set down.

It is a further object of the invention to provide such a device which is equipped additionally with optional, fast, manual load-release means.

It is another object of the invention to provide such a device which may be quickly and easily set in locked position, quickly and easily released from locked position, and quickly reset in locked position after the load carried by the device is discharged.

It is a still further object of the invention to provide such a device which is sturdy of construction, and having a minimum number of working parts which may be easily and inexpensively manufactured and assembled.

With these and other objects in view, the invention consists of the construction, arrangement and combination of the various parts of the device whereby the objects contemplated are attained, as hereinafter set forth, pointed out in the appended claims, and illustrated in the accompanying drawings.

In the drawings:

FIGURE 1 is a front elevational view of the device of the present invention in closed position, with a load suspended therefrom.

FIGURE 2 is a side view of the device as shown in FIGURE 1.

FIGURE 3 is an enlarged sectional view of the device in position for reload.

FIGURE 4 is a view similar to FIGURE 3, but with the device in loaded position.

FIGURE 5 is another view similar to FIGURES 3 and 4, but with the device in partially opened position.

FIGURE 6 is a cross-sectional view taken on the line 6—6 of FIGURE 4.

FIGURE 7 is an enlarged fragmentary view showing the hook latching means of the device in partially opened position.

FIGURE 8 is a detailed sectional view taken on the line 8—8 of FIGURE 4.

FIGURE 9 is a detailed sectional view taken on the line 9—9 of FIGURE 4.

FIGURE 10 is a fragmentary view showing the means of locking the automatic load release assembly when manual release is desired.

A body member 10 has a recessed opening 11 at one end thereof. An arcuate hook or cargo support member 12 is pivotally mounted at one of its ends to the body member 10 adjacent one side of said recessed opening 11 and disposed so as to swing to close said recessed opening 11 when the device is in closed position.

A latch member 20 is pivotally mounted at one end of said latch member 20 to said hook member 12 adjacent the other end of hook or cargo support member 12. Said latch member 20 has an elongate body 21, having a

2

longitudinal surface 22, an oblique abutment face 23, and a protruding shoulder 24 which is formed with an abutting surface 25, also preferably oblique.

Rigidly mounted on body member 19, adjacent the side of recessed opening 11 opposite the side at which hook or cargo support member 12 is mounted, is a retaining member 30 which has an abutment surface 31 disposed so as to mate with and abut against surface 25 of latch member 20 when the device is in closed position.

A latching bar 40 is pivotally mounted intermediate the ends thereof on body 10 in spaced relation to said retaining member 30, and to surface 22 of latching member 20. One end 41 of said bar 40 is disposed so as to abut against surface 22 of latch 20 and hold said latch 20 in abutment with retaining member 30 when the device is in closed position. The other end 42 of said bar 40 is disposed so as to abut against a trigger member 50, hereinafter described. A stop or pin 43 may be mounted on body 10 and disposed so as to arrest clockwise movement of bar 40 at a predetermined point.

Trigger 50 is of right-angle configuration, formed of arms 51 and 52, disposed at right angles to each other. Trigger 50 is pivotally mounted on a plunger 60, hereinafter described in detail, and is mounted intermediate said arms 51 and 52. Arm 52 is disposed so as to be clear of end 42 of bar 40 when the device is in the reload position shown in FIGURE 3; to overlie said end 42 when the device is in the loaded position shown in FIGURE 4; and to abut against said end 42 when the device is in the opening position shown in FIGURE 5.

A stop or pin 53 is mounted on body 10 and disposed so as to move trigger 50 out of its overlying position, and also to arrest counterclockwise movement of trigger 50 when trigger 50 has attained the position shown in FIGURE 3.

A plunger 60 is slidably disposed in an open-ended chamber 61 in body 10. Mounted on plunger 60 is a ring 62 for attachment of a crane cable thereto. Said ring 62 may be disposed in a slotted opening 63 in body 10 and chamber 61 so as to allow full sliding movement of plunger 60 in chamber 61.

At its lower end plunger 60 has a flange 64 disposed in recessed opening 11. Springs 65 are disposed in opening 66 in body 10, and abut against flange 64 so as to bias plunger 60 downwardly against the upward pull of a cable attached to ring 62 with a load suspended from the device.

A spring 67 is disposed in an open-ended chamber 68 in plunger 60 and abuts against trigger 50 so as to bias trigger 50 in a counterclockwise direction.

A locking bar 70 is slidably disposed in an open-ended lateral bore 71 in plunger 60, said bore 71 being disposed so that bar 70 may be slid outwardly to abut against the outer edge of body 10 and prevent the downward movement of plunger 60 when manual operation of the device is desired. For easy movement of bar 70, a rod 72, equipped with a knob 73, may be mounted on bar 70 intermediate the ends thereof and disposed in slotted opening 74, with rod 72 protruding outwardly from slotted opening 74 and knob 73 disposed outside body 10.

For manual operation of the device, halyard 80 is attached to latching bar 40 adjacent end 41 thereof, by any suitable means, such as a ball and socket assembly 81. Halyard 80 passes through an opening 82 in body 10 and extends upwardly and outwardly from body 10. A block 83 may be mounted externally of body 10. Block 83 has an opening 84 aligned with opening 82 in body 10, and halyard 80 is also disposed therein. If desired, as a matter of convenience in operation, stop 85 may be mounted on halyard 80 by any suitable means, such as by set-screw 86.

A recess 90 is cut in body 10, and disposed therein in spring 91 which abuts on latching bar 40 adjacent end

41 thereof and biases said latching bar 40 in a clockwise direction.

A ring 100 may be used to secure a load to hook 12. When it is desired to apply the automatic opening features of the device, locking bar 70 is retracted, permitting free sliding movement of plunger 60 in chamber 61. Without pull tension on ring 62, plunger 60 will be biased downwardly by springs 65, and trigger 50, arrested by pin 53, will be in the position shown in FIGURE 3, with its arm 52 completely clear of end 42 of latching bar 40. With hook 12 in closed position, latching bar 40, biased downwardly by spring 91, will have its end 41 abutting first against face 23 and then against surface 22 of latch 20, thus bringing latch 20 into abutment with retaining member 30. Further downward, clockwise movement of bar 40 will be arrested by pin 43, so that end 41 of bar 40 will remain firmly seated against surface 22 of latch 20, keeping latch 20 in firm latching contact with retaining member 30.

When a load is suspended from hook 12, and pull tension greater than the biasing power of springs 65 builds up in plunger 60, plunger 60 will slide upwardly until it assumes the position illustrated in FIGURE 4, when trigger 50, clear of pin 53, will turn counterclockwise, impelled by the biasing action of spring 67, until arm 52 of trigger 50, clear of end 42 of bar 40, will overlie said end 42 of bar 40.

When the load is set down, so that pull tension is released from plunger 60, plunger 60, impelled by springs 65, will move downwardly, and arm 52 of trigger 50 strikes end 42 of bar 40, causing bar 40 to turn, against the biasing action of spring 91, in a counterclockwise direction, whereupon end 41 of bar 40 will ride upon surface 22 and along face 23 until latch 20 is free to move out of engagement with retaining member 30, whereupon hook or cargo support member 12 will be free to swing open and release ring 100 and the load thereby suspended. Downward movement of trigger 50 will continue until arm 52 has passed end 42 of bar 40, whereupon it will assume the position shown in FIGURE 3, and the device will be ready for reloading.

When it is desired to use the device with manual operation by means of halyard 80, plunger 60 is drawn upward until bore 71 is clear of body 10. Bar 70 is then slid to abutting position against the outside surface of body 10, whereby plunger 60 is held in elevated position and cannot move downwardly. Plunger 60 and trigger 50 will thus be substantially in the position shown in FIGURE 4, with arm 52 thereof overlying end 42 of bar 40.

When pull tension is applied to halyard 80, against the biasing force of spring 91, end 41 of bar 40 will be drawn upwardly along surface 22 and over face 23 of latch 20, until latch 20 is free of retaining member 30, thus permitting hook or cargo support member 12 to swing free and discharge the load suspended from ring 100. Release of said pull tension on halyard 80 will permit retaining member 30, latch 20 and bar 40 to assume their latched positions when hook or cargo support member 12 is swung to closed position.

Although I have herein shown and described my invention in what I have conceived to be the most practical and preferred embodiment, it is recognized that departures

may be made therefrom within the scope of my invention, which is not to be limited to the details disclosed herein but is to be accorded the full scope of the claims so as to embrace any and all equivalent structures and devices.

5 What is claimed is:

1. A quick release cargo handling device adapted to be positioned between lifting means and cargo, wherein the weight of said cargo when suspended applies load tension to said device, said device comprising: a body member; a cargo support member pivotally mounted at one end on said body member and adapted to have said cargo suspended therefrom; releasable latching means interconnected between the other end of said cargo support member and said body member; and means for automatically actuating said latching means and releasing said cargo support member for pivotal movement when said cargo is landed and said load tension is relieved comprising a plunger shiftably carried by said body member, spring means interconnected between said plunger and said body member urging said plunger toward said latching means, means for attaching said lifting means to said plunger wherein the weight of said cargo moves said plunger away from said latching means against the force of said spring means, and trigger means carried by said plunger operable to engage said latching means and release said cargo support member in response to shifting movement of said plunger toward said latching means by force of said spring means when said cargo is landed and said load tension relieved.

2. The subject matter of claim 1 wherein said trigger means comprises arm means pivotally carried by said plunger and movable between first and second positions and means interconnecting said plunger and said arm means and pivoting said arm means from said first position to said second position when said load tension is applied.

3. The subject matter of claim 1 wherein said trigger means comprises an L-shaped member having first and second arms pivotally mounted on said plunger at the juncture of said arms, and a spring interposed between said plunger and said second arm to thereby pivot said L-shaped member to a predetermined position when load tension is applied wherein said first arm overlies said latch means.

4. The subject matter of claim 1 including manually operable means carried by said body member and operably connected to said latch means wherein actuation thereof releases said cargo support means and said cargo.

5. The subject matter of claim 3 wherein said latching means includes a locking bar pivotally mounted on said body member and having one end thereof positionable under said first arm of said L-shaped member.

6. The subject matter of claim 3 including a stop mounted on said body member and engageable with said second arm for pivoting said first arm away from its overlying position relative to said latch means.
